(57) **ABSTRACT**

A new distinct variety of grapevine named 'ARD7' abundantly forms attractive crispy seedless berries with a black skin coloration in lax and small clusters which display a naturally sweet flavor, the fruit commonly is ready for harvesting during June in San Joaquin Valley of Central California, U.S.A., and displays good eating qualities as a table grape having a firmness that renders the fruit well amenable for handling, shipping, and storage.

1 Drawing Sheet

1

Classification: The present invention relates to a new *Vitis vinifera* Grapevine.

Variety denomination: The new Grapevine has a varietal denomination 'ARD7'.

BACKGROUND OF THE INVENTION

A breeding program was initiated during the late 1990's near Bakersfield in San Joaquin Valley of Central California. In 2013, during this breeding program, a new variety of *Vitis vinifera* was created by deliberate cross breeding of two parent plants by emasculation of the pollen bearing organ of the female and introducing pollen from another male origin. The female parent of the new variety was 10-19+5, which is a large size, meaty and juicy black table grape with a naturally sweet flavor (non-patented in the United States). The male parent (i.e. the pollen parent) of the new variety was 11704/20, a very fertile creamy white table grape variety with a small seed trace (non-patented in the United States).

2

The parentage of the new variety can be summarized as follows:

10-19+5 X 11704/20

5 An artificial pollination was created, and the result was an embryo which possessed unique genetic qualities. The rudiments resulting from the above pollination were embryo rescued.

In 2014 the plant was transplanted to Bakersfield in San Joaquin Valley of Central California.

It was found that the new grapevine of the present invention possesses the following combination of characteristics:

- (a) Forms attractive crispy seedless berries with a black skin coloration; in lax and small clusters which display a naturally sweet flavor;
- (b) Commonly bears fruit during the month of June in the San Joaquin Valley of Central California, U.S.A.;
- (c) Bears fruit that is firm and is well amenable for storage, handling, and shipping; and
- (d) Produces 32 bunches per vine, and an average of about 2 bunches per shoot, at a total of 32 lbs. fruit per vine.

The new variety during observation to date has displayed no visible disease, and has displayed an ability to well resist cold, drought, and heat, but is sensitive to direct exposure to sun and wind. The fruit of the new variety has been found to display excellent handling and shipping qualities combined with desirable dessert eating qualities.

The new variety of the present invention has been found to undergo asexual propagation beginning in 2015 near Bakersfield in the San Joaquin Valley of Central California, U.S.A. by bud grafting on mature 'Thompson Seedless' rootstock (non-patented in the United States). Such asexual propagation has been conducted thereafter in successive

TABLE 1

'ARD7' compared with parents & closely related variety:

				'AUTUMN ROYAL'
	'ARD7'	10-19+5	11704/20	(non-patented)
Seed trace	Sterile	Rudimentary	Rudimentary	Prominent
Berry Texture	Crispy	Meaty and Juicy	Meaty	Firm & Translucent
Bunch density	Lax	Medium	Medium loose	Medium

years to date and has shown that the characteristics of the new variety are strictly transmissible from one generation to another. Accordingly, the new variety undergoes asexual propagation in a true to type manner.

SUMMARY OF THE INVENTION

The new variety 'ARD7' is a black seedless table grape with a high production, e.g., about 32 bunches per vine, and an average of about 2 bunches per shoot. Asexual reproduction by micro propagation of the new variety as performed near Bakersfield, California, U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

The drawing shows leaves, stems and grapes of 'ARD7'.

DETAILED BOTANICAL DESCRIPTION

The chart used in the identification of colors is The R.H.S. Colour Chart of The ROYAL HORTICULTURAL SOCIETY (3rd Edition). The description is based on the observation of plants growing on 'Thompson Seedless' rootstock outdoors near San Joaquin Valley of Central California, U.S.A.

VINE CHARACTERISTICS:

Vigor	Vigorous upright shoots
Productive capacity	Bearing at a natural, average capacity.
Trunk	Spur pruning. Strong and developed. Diameter is 3.1 inches at 4.3 inches above ground. Rough with a fibrous, shaggy exterior. Light maple brown coloring Greyed orange 166C

Date of bud burst in Bakersfield California: February, 21st.

YOUNG SHOOT CHARACTERISTICS:

Openness of tip	Fully Open
Density of prostrate hairs on tip	Sparse
Anthocyanin coloration of prostrate hairs on tip	None

YOUNG LEAF CHARACTERISTICS:

Color of upper side of blade	Yellow green 152A
Color of lower side of blade	Yellow green 152B
Density of erect hairs between main veins on upper side of blade	Absent or very sparse

-continued

YOUNG LEAF CHARACTERISTICS:

5	Density of erect hairs between main veins on lower side of blade	Absent or very sparse
10	Density of prostrate hairs on main veins on upper side of blade	Absent or very sparse
	Density of prostrate hairs on main veins on lower side of blade	Absent or very sparse

SHOOT CHARACTERISTICS:

15	Attitude (before tying)	Erect
	Color of dorsal side of internodes	Yellow green 144A
	Color of ventral side of internodes	Yellow green 145A
	Color of dorsal side of nodes	Yellow green 144A
	Color of ventral side of nodes	Yellow green 144B
	Density of erect hairs on internodes	Sparse
	Density of prostrate hairs on internodes	Sparse
	Length of tendrils	6.07 inches
	Diameter of tendrils	0.07 inches
	Color of tendrils	Yellow green 152A
	Number of tendrils at bloom	3
	Positioning of first flowering and fruiting node	The first bunch is in the 3rd node
	Inflorescence number per flowering shoot	2

FLOWER CHARACTERISTICS:

30	Reproductive organs	Fully developed stamens and fully developed gynoecium
	Flower length	0.22 inches
	Flower diameter	0.13 inches
	Pistil length	0.09 inches
	Pistil color	Green 143B
	Pollen Amount	Rich
	Pollen color	Yellow 11A
	Stamen color	Yellow green 145C
	Stamen length	0.07 inches
	Number of stamen	5

First bloom in Bakersfield, California: April, 26th.

Date of full bloom in Bakersfield, California: May, 1st.

MATURE LEAF CHARACTERISTICS:

50	Size of blade	6 inches x 6.5 inches
	Shape of blade	Pentagonal
	Base descriptors	Pentagonal
	Leaf margin	Serrate
	Leaf apex	Acute
	Blistering of upper side of blade	Absent or very sparse
	Depth of upper lateral sinuses	Medium
	Number of lobes	Five
	(Only varieties with lobed leaves)	Closed
	Arrangement of lobes of upper lateral sinuses	
	Arrangement of lobes of petiole sinus	Slightly open
	Length of teeth	0.5 inches
	Ratio length/width of teeth	Medium
	Shape of teeth	Mixture of both sides straight and both sides convex
	Density of prostrate hairs between main veins on lower side of blade	Absent or very sparse
60	Density of erect hairs on main veins on lower side of blade	Absent or very sparse

-continued

MATURE LEAF CHARACTERISTICS:		PEDICEL CHARACTERISTICS:	
Density of erect hairs between the main veins on upper side of blade	Absent or very sparse	5	Length 0.4 inches Diameter 0.08 inches Color Yellow green 145A Pedicel texture Rough
Density of prostrate hairs on main veins on upper side of blade		WOODY SHOOT CHARACTERISTICS:	
Length of petiole compared to length of middle vein	Moderately shorter	10	Woody shoot texture Smooth Woody shoot color Greyed orange 165A Woody shoot length 128 inches Diameter 0.4 inches Internode length 3 inches
Top side color Green 137B Bottom side color Yellow green 147C		Market use of observed plants: Fresh market. Age and growing conditions: Six years growing under Y system in South Joaquin Valley (hot, dry summers).	
Texture of upper side of blade Rough		20	Shipping characteristics: Fruit was in cold storage. Stored in poly bags inside Styrofoam boxes with sulfur pads. After 60 Days: rachises were 75% green; 7% berry shattering; no berry wrinkling or cracks were apparent.
Texture of lower side of blade Rough		25	DNA profile: To further characterize the new variety DNA was extracted from plant samples and a DNA profile was obtained in, California USA using base pairs for 10 standard microsatellite DNA markers. The data is presented hereafter.
Vein color on upper blade Yellow green 146D		TABLE 2 DNA profile for 'ARD7'	
Vein color on lower blade Yellow green 145C		30	*Microsatellite DNA Marker Allele Sizes in Base Pairs
Venation pattern for upper blade Netlike venation		35	M 1 232 234 M 2 239 249 M 3 179 194 M 4 210 212 M 5 271 271 M 6 133 151 M 7 189 201 M 8 255 257 M 9 214 214 M 10 237 239
Venation pattern for lower blade Netlike venation		40	
Petiole length 3.86 inches			
Petiole diameter 0.08 inches			
Petiole color Yellow green 145B			
Petiole texture Smooth			
Date of beginning of berry ripening in Bakersfield California: June, 5 th .		The 'ARD7' variety has not been observed under all possible environmental conditions to date. Accordingly, it is possible that the phenotypic expression may vary somewhat with changes in light intensity and duration, cultural practices, and other environmental conditions.	
BUNCH CHARACTERISTICS:		Additional information relating to plant and fruit disease and pest resistance or susceptibility has not been observed to date. Specification of the plant hardiness zone and the heat/cold resistance has not been observed to date.	
Size (peduncle excluded) Small		What is claimed is:	
Density of berries on bunch Lax		1. A new and distinct grapevine plant, botanically known as <i>Vitis vinifera</i> , identified as 'ARD7', substantially as shown and described herein.	
Bunch length 6.5 inches			
Bunch diameter 4.63 inches			
Length of peduncle of primary bunch 6.03 inches			
Diameter of peduncle of primary bunch 0.21 inches			
Peduncle of primary bunch color Yellow green 145B			
Peduncle texture Rough			
Bunches per vine 32			
Average bunch weight 1 lbs			
BERRY CHARACTERISTICS:			
Size Small			
Length 0.83 inches			
Weight 0.15 oz			
Diameter 0.7 inches			
Shape Broad ellipsoid			
Color of skin (without bloom) Black 202A			
Flesh color Yellow green 145D			
Brix 25.3			
Titratable acidity percentage 0.3%			
Juice 4.44 pH			
Ease of detachment from pedicel Difficult			
Thickness of skin Medium			
Anthocyanin coloration of flesh None			
Firmness of flesh Moderately firm			
Particular flavor None			
Formation of seeds None			
Berries per bunch 111
